INVENTOR

UNITED STATES PATENT OFFICE

WALTER F. TROTTER, OF CINCINNATI, OHIO, ASSIGNOR TO THE OHIO ELECTRIC HAMMER CORPORATION, A CORPORATION OF OHIO

POWER HAMMER

Application filed March 16, 1929. Serial No. 347,668.

This invention relates to power driven hammers or drills for breaking pavement and concrete surfacing or drilling the same by localized impact and intermittent rotation of the tool, and is particularly directed to an improved mechanism for converting rotary motion into reciprocatory motion for impacting the tool, and to a mechanism for rapidly and accurately intermitting rotation of the tool for alternate rotation and impact.

The motion converting mechanism is in the form of a driven cam device having two cam surfaces, the cam reciprocating a ram or driver by alternate engagement with the respective cam faces, and the cam surfaces made yieldable under impact or ram engagement. One cam face is formed with a portion of sharp curve for initially imparting a high velocity impulse to the ram, directing it toward an anvil or head end of the tool, and the other cam face is so cleared in the adjacent portion that there will be no engagement of the ram with the first cam surface to interfere with the sudden impact. Therefore, as induced by this cam impulse, the ram moves of its own momentum against the tool anvil and imparts a heavy impact thereto. The ram and tool anvil are so related that the impact comes during the free movement of the ram. If the tool is not in position as might occur, due to the rapid hammering, or the fact that the tool was not held firmly against the work, the ram is decelerated by engagement with a uniformly curved portion of the first cam, this portion straightening out into a horizontal, and uniformly curving in a reverse direction to slowly retract the ram for the next succeeding blow.

It is therefore an object of this invention to provide a device for reciprocating the ram or driver of the machine for impacting a tool, which device initially sharply and uniformly accelerates the ram in downward movement and thereafter releases the same, permitting it to strike the tool head or anvil under the influence of its own momentum.

It is another object to provide for efficient deceleration of the actuated ram moving under the normal, high, necessary velocity particularly when there is a failure of impact or

improper placement of the anvil or tool head with resultant badly timed impact, the objective here being a uniform deceleration or cushioning to a complete stop and retraction without detriment to the mechanism or shock to the operator, smoothing out the driver action by merging and checking the recoil movement in the retraction actuation of the ram.

Another object is to provide in this type of ram actuating device a yieldability of contact between the ram and the actuating means.

Another object is to provide an improved mounting for the ram or driver for high velocity reciprocation.

An intermittent motion device is provided and inserted in conjunction with the foregoing device for intermittent rotation of a drill impacted by the ram, and this device is incorporated as a part of a worm and worm gear transmission inserted between the cam driving shaft and the drill.

The provision is made, to accomplish this result, of a worm having a thread of varying pitch, by means of which a part revolution of the worm advances the worm wheel one tooth. The present invention utilizes the remainder of a particular thread convolution as the idling period for the worm gear. This is accomplished by terminating the rise or pitch of the thread upon a part revolution, and continuing the remainder in a plane at right angles to the axis of the worm and therefore with no pitch. The part of the thread having no pitch merely passes between the teeth of the worm gear without rotating effect until the adjoining convolution is engaged. As long as a lead or rise of a particular convolution of the worm thread is sufficient to advance the worm gear at least one tooth, the remainder of the convolution may be straight or even of negative pitch, the latter being of utility when oscillation of a gear is desired.

It is, therefore, another object of this invention to provide intermittent rotary motion by means of a continuously meshing worm and worm gear.

It is further provided that the teeth of the

worm gear are straight cut in part and diagonally cut in part so that the working surfaces of said teeth are smoothly engageable either by the pitch portion of the worm thread or by the straight portion thereof.

5 Another object of this invention is to efficiently synchronize the action of the drill impacting device and the intermittent rotative motion device to insure intermittent impact and rotation of the tool.

10 Further objects and advantages will be more fully set forth in the description of the accompanying drawings, in which:

15 Figure 1 is a perspective view of a concussion or drilling apparatus embodying the features of the present invention.

Figure 2 is a central sectional view taken longitudinally of the apparatus.

20 Figure 3 is a transverse sectional view taken on line 3—3, Figure 2, illustrating the fan for cooling the motor.

25 Figure 4 is a sectional view taken on line 4—4, Figure 2, illustrating the guided mounting of the ram in the frame.

30 Figure 5 is a sectional view taken on line 5—5, Figure 2, showing the relation of the cam to the ram.

35 Figure 6 is a transverse sectional view taken on line 6—6, Figure 2, illustrating the transmission for intermittently rotating the anvil from the cam shaft.

Figure 7 is an enlarged side elevation of the cam removed from the machine.

40 Figure 8 is a diagrammatic or developed view illustrating the cam layout and relation of the respective cam surfaces.

Figure 9 is an enlarged detail view of the worm and worm gear used for imparting intermittent rotation to the anvil.

45 Figure 10 is a side elevation of Figure 9.

Figure 11 is a diagrammatic view or development of the thread of the worm.

50 The apparatus embodying the features of the present invention is shown in the nature of a portable electrically driven concussion or drilling device. It embodies, in general, a power source as an electric motor mounted in the upper end thereof, the motor driving a cam shaft through an appropriate speed reduction gearing, and the cam shaft extending longitudinally of the normally vertically extending body of the apparatus and journalled in the respective ends thereof.

55 The concussion device primarily comprises a double-faced cam having the advantages previously outlined, and the cam in operative engagement with a guided ram or driver, this ram or driver being disposed for reciprocal motion longitudinally of the body of the device. Below the ram and in alignment therewith an anvil is disposed in the frame.

60 In the case of the drill, the anvil is mounted for rotation and is rotated by means of a gearing arrangement from the cam shaft, the anvil being in slide connection with its rota-

tive mounting for longitudinal impulses or concussions imparted thereto. The gearing is of a special nature for intermittent rotation mechanically synchronized with the concussions imparted to the anvil.

65 Any sort of tool may be utilized with the device, the rotative mounting being incorporated in the event of a drill being used, and this mechanism left out when a pavement breaking chisel is used. The anvil extends through the lower end of the frame and provides a chuck in the lower end for receiving the tool. In the instance of the pavement breaking tool being used a conveniently manipulated attachment device is used for affixing the tool to the frame relative to the anvil.

70 Referring to the drawings, the frame of the device is made up of a motor casing 15, a driver and operating means casing 16, and an anvil transmission casing 17, these casings secured together in vertical relation. Handles indicated at 15^a are provided on the casing, one at the top and one extending laterally therefrom. A rotor or armature 18 is vertically journalled in the motor casing and has its shaft 19 extending downwardly through a lower bearing 20 and a pinion gear 21 secured on the extending end. A bearing plate 22 is secured between the upper or motor casing and the intermediate or ram casing, this plate having the bearing 20 secured therein journalling the lower end of the motor shaft and also a bearing 23 journalling the upper end of a cam shaft 24. The cam shaft 24 extends longitudinally within the intermediate casing and is journalled in the lower or anvil transmission casing.

75 A fan 25 is secured on the motor shaft between the body of the motor and the bearing plate, the air circulation being through apertures 26 in the lower portion of the side walls of the motor casing and apertures 26^a in the top wall thereof. A gear 27 is keyed to the cam shaft and is in mesh with the pinion 21 of the motor.

80 The driver cam 28 is keyed to the shaft intermediate the shaft length, being maintained against longitudinal displacement by means of a collar 29 engaging its lower hub and holding it against a spacer sleeve 30 fixed to the shaft 24 between its upper hub and the gear 27. The cam is sectional, the sections 31, 32, thereof each having peripheral flanges oppositely disposed, the surfaces of the flanges being the ram actuating and controlling mediums as hereinafter described. The cams are yieldingly spaced apart by means of a coil spring 33 under compression seated in deep concentric grooves 34 in the opposing faces of the sections. The co-related peripheral flanges of the cams pass between a pair of rollers 35—35 mounted on the vertically reciprocably mounted ram 36.

85 The ram is vertically guided between pairs of ball bearing rollers 37, a pair at each side

thereof, these ball bearing rollers engaging in grooves 38 longitudinally formed in the side walls of the ram and being journaled in the side walls of the casing. The journaling of the ball bearing rollers is by means of headed studs 39 passing through the side wall of the casing and rigidly held in position by means of nuts 40, there being an intermediate shoulder 41 on the shank of each stud engaging the inner side of bushings fixed in the casing wall and preventing clamping of the inner ring of the ball bearing rollers, this loose mounting of the inner bearing ring permitting greater freedom of motion of the ram. The ram is floatingly guided for reciprocal motion in these ball bearing connections for reducing the friction and allowing the ram to move with a maximum of freedom, and when released from the influence of the cam moves under its own momentum for impact with the tool.

An anvil or impact transmitting bar and spindle 42 is mounted in alignment with the ram and has its upper end positioned for impact by the ram. The anvil has a hexagon shaped upper end 43 for rotative connection with a sleeve 44 rotatively journaled in bearings 45 secured in the transmission casing. The anvil extends through a downwardly disposed boss 46 of the casing and has a chuck 47 formed on its lower end.

A retainer sleeve 48 is screw-threaded onto the lower end of the boss and has an inwardly extending abutment flange 49 at its lower end. An annular shoulder 50 is formed on the chuck portion of the anvil and is adapted to engage the inwardly turned flange, this inwardly turned flange 49 being spaced away from the lower end of the boss, and the annular shoulder of the anvil engaging therewith prevents the anvil from dropping from the device. The spacing of the inner flange from the end of the boss 46 is sufficient to permit the unhampered movement of the anvil under the impacts of the concussion device.

A drill 51 is socketed in the chuck in the conventional manner and engagement of the tool against the surface to be drilled maintains the annular shoulder against the lower face of the boss, which exactly positions the anvil head relative to the driver for impact.

The cam for actuating the ram, as detailed in Figures 7 and 8, has its surfaces pitched in the following manner: The developed view of the cam illustrates the cam surfaces from the points at which they engage the ram at the beginning of a cycle. The cam moving to the left, as viewed from the ram side, presents a sharply curved lower cam surface 52 which engages the lower roller of the ram and imparts downward movement to the ram.

If the anvil is properly positioned, the impact of the ram with the tool causes the ram

to dwell in the position of impact where the slowly rising surface 53 of the upper cam comes smoothly into engagement with the upper roller of the ram and retracts the driver for the succeeding blow.

It will be apparent from Figure 8, that after the ram has departed from engagement with the lower cam, the distance between the upper and lower cam surfaces decreases materially so that there is considerable clearance for the ram to move in, prior to engagement of the upper or return cam surface 53 with the upper roller.

It frequently happens that the anvil is not in exact position to receive the impact or concussion, this occurring when there is chattering of the tool or when the tool is not held firmly against the work. For this reason, the upper cam surface is provided with a portion 54 adjacent the point of departure 55 on the lower cam which is designed to engage the upper roller of the ram, this portion 54 being of uniform curve to a horizontal to slowly and smoothly decelerate the ram in its downward direction in the event of failure of impact. This decelerating surface smooths out into a horizontal and then rises to represent the previously described slow rising surface 53 for retracting the ram. The ends of the developed view represent the beginning of the cycle, being taken at a coincidental line on the cam.

The throwing cam 32 has its throwing face shaped to give the ram a uniformly accelerated motion downwardly or in a direction to impact with the tool which continues while the ram is in contact with the throwing face. After leaving the throwing face of the cam 32 the ram is free to continue for a limited distance under the influence of its own momentum. It is during this period the impact with the tool or anvil takes place. If the weight relation between the ram and tool is correct, the ram comes practically to rest and remains so until contact is made between the ram and the upper or returning cam. The surface 54 of the upper cam 31 from the point or end of the throwing face of the throwing cam 32 continues to recede and with the rotation of the cam provides for the free motion of the ram for impact with the tool and comes to rest before again acted upon by the cam or the upper cam 31. The receding portion of the upper cam also serves to give the ram a uniform negative acceleration or gradually retards the downward motion of the ram if the tool is not in position to stop or receive the impact. This action continues with the rotation of the cam until the ram is brought to rest by non-ram moving portion of the upper cam, whereupon the surface of the upper cam ascends to move the ram in an opposite direction.

The two cams are splined upon the shaft with the spring under tension interposed be-

tween the cams pressing each cam in the direction in which the cam throws or moves the ram. Each cam, therefore, is capable of yielding motion or automatic adjustment to relieve it of sudden shocks interposed thereon when coming into engagement with the ram either at a point at which one of the cams decelerates the motion of the ram or counteracts the motion of the ram. The cams can thus be made separately facilitating in their manufacture. The cams are loosely keyed upon the shaft with their cam faces outwardly and stops placed on the shaft, spaced a distance apart slightly greater than the combined length of the cams along the shaft. The spring interposed between two cams serves to cushion the cams.

Intermittent motion is imparted to the rotatively mounted sleeve 44, which is in rotative connection with the anvil, by means of a cross shaft 64 journaled in the side walls of the frame. A worm 65 is pinned to the cam shaft 24 at its lower end, this worm being in engagement with a worm wheel 66 keyed to the cross shaft. At the other end of the cross shaft 64 a worm 67 is keyed thereto and properly spaced thereon by means of spacer sleeves 68 for meshing with a worm wheel 69 keyed to the anvil sleeve 44. It is the particular formation of these last mentioned worm and worm gear elements which provides the intermittent motion. The worm of this combination is shown as of a single thread formation. The pitch of the worm is varied and half of a convolution thereof is devoted to a gear turning pitch and the other half is a straight thread for idling of the worm wheel.

Regarding a given thread, as shown in the developed view Figures 9 and 11, the thread has a pitch for one-half convolution as at 70, and then is straightened out to a plane at right angles to the axis of the worm for a half convolution as at 71 where it joins the next pitch or rise portion. By utilizing half a convolution of the thread spiral for the lead, the worm wheel is advanced one tooth and the remainder of the revolution is devoted to a dwell.

Due to the fact of the use of a worm of this nature the thread presented to the worm gear is at varying angles, that is to say, at the angle of the desired pitch or at right angles to the axis of the worm. The teeth of the worm wheel are therefore cut or milled (see Figure 10) parallel with the axis thereof as at 72 and also at a tangent as at 73, the angle of tangent corresponding to the pitch of the worm thread. This provides teeth edges always in substantial driving engagement with the thread of the worm.

Another variation of the lead, which may be used, is of the ensuing nature. If the driving lead or pitch of each convolution is of greater length than is necessary for advanc-

ing the worm wheel one tooth, the excess advance of the worm wheel over the one tooth, requirement could be reversed by giving the remainder of the convolution a reverse or negative lead equal to the excess.

It can be seen that by this arrangement the motion of the worm wheel could be made forward and stationary for each revolution or convolution of the worm, or it could be made forward and backward, or it could be made forward, stationary and backward, provided, however, in all instances the restriction of having an advance of the worm wheel one tooth. The excess beyond that could be varied in any manner as aforesaid.

By properly positioning the cam on the cam shaft and relating the transmission thereto, the impact is given to the anvil while the straight portions of the worm are in mesh so that the rotative dwell comes when the impact is being delivered. This synchronization is highly desirable for a drill since the turning of the drill at the moment of impact would unduly wear or break off the sharpened edges thereof.

Having described my invention, I claim:

1. In a tool of the class described, a ram floatingly supported for reciprocal motions for impact with a cutting tool, and a pair of cams splined upon an axis and rotatable as a unit, one for moving the ram in one direction and the other in a reverse direction, said cams each yieldable in a direction counter to the direction in which it moves the ram.

2. In a tool of the class described, a ram, floatingly supported for reciprocal motions for impact with a cutting tool, a pair of cams rotatable as a unit, one for moving the ram in one direction and the other in a reverse direction, and means for yieldingly urging said cams in opposite directions axially, said means taking up the shocks when the cams respectively become effective upon the ram with the reversal of strokes.

In witness whereof, I hereunto subscribe my name.

WALTER F. TROTTER.
